UNITED STATES PATENT OFFICE.

GEORGE L. WEBB, OF SPENCER, NORTH CAROLINA.

SAND-DRIER.

No. 834,781.

Specification of Letters Patent.

Patented Oct. 30, 1906.

Application filed August 17, 1906. Serial No. 331,089.

To all whom it may concern:

Be it known that I, GEORGE L. WEBB, a citizen of the United States, residing at Spencer, in the county of Rowan and State of North Carolina, have invented a new and useful Sand-Drier, of which the following is a specification.

This invention relates to apparatus for drying sand, gravel, &c.; and its object is to provide apparatus of this character which will quickly and thoroughly dry large quantities of material.

A still further object is to provide a drier having novel means for discharging the dry sand.

Another object is to provide means whereby large stones or other material which may interfere with the discharge of the sand or gravel can be readily removed by the operator.

With the above and other objects in view the invention consists of a casing having interior walls formed of wire-netting, while the bottom thereof consists of a series of grate-bars mounted to rock simultaneously, so as to agitate the contents of the casing and cause the discharge thereof. Parallel vertical coils of pipes are disposed within the casing and connected to a suitable steam-supply, and each coil is provided with a vent to permit the steam to exhaust from the coils. Means are provided whereby access may be conveniently had to the upper faces of the grate-bars for the purpose of permitting the removal of any undesirable accumulations thereon.

The invention also consists in providing novel means for facilitating the escape of vapor from the heated body of material.

The invention also consists of certain novel features of construction and combinations of parts, which will be hereinafter more fully described, and pointed out in the claims.

In the accompanying drawings is shown the preferred form of the invention.

In said drawings, Figure 1 is a view of the apparatus, showing the same partly in side elevation and partly in section. Fig. 2 is a vertical transverse section, and Fig. 3 is a horizontal section through one corner of the apparatus and showing one end of a grate-bar in plan.

Referring to the figures by characters of reference, 1 are vertical standards secured to sills or base-strips 2 and arranged in parallel rows, the standards of each side being

connected by inverted-L-shaped side strips 3, having substantially semicircular recesses 4 in their upper faces at desired intervals. Outer walls 5 are secured upon the outer faces of the standards 1 and connect the end standards, so as to form a rectangular casing. An inner wall 6, formed of a screen of fine mesh, is secured upon the inner faces of the end standards 1, and angle-irons 7 are clamped upon the side edges of the end screens 6 and have washers 8 secured thereon by means of bolts 9. These bolts engage wire screens 6 of fine mesh, which extend over the inner faces of the side walls and are spaced therefrom by the washers 8.

Grate-bars 11 are supported between the L-shaped strips 3 and have trunnions 12 projecting from the centers of the ends thereof and bearing within the notches or recesses 4, hereinbefore referred to. As shown particularly in Figs. 1 and 3, each grate-bar is formed with a number of apertures 13, and each grate-bar has an arm 14 extending downward therefrom. All of these arms are pivotally connected to a rod 15, one end of which is pivoted, as at 16, to a lever 17, journaled within a bracket 18, extending from one end of the casing. The grate-bars are so proportioned that when in their normal or horizontal positions their adjoining edges lie close together, so that a substantially continuous casing-bottom is produced. All of the screens 6 and 10 extend downward to the lower edges of the outer walls of the casing. One of the side walls 5, however, terminates at a point above and somewhat removed from the plane occupied by the upper faces of the grate-bars, and the space below this wall is adapted to be closed by a removable closure 19, which is supported within brackets 20, secured to the standards 1, and is adapted to fit under and lie flush with the wall 5 thereabove. In order that the closure 19 may be easily removed, threaded studs 21 extend from the lower edge of said wall 5, and the closure 19 is formed with slots 22 directly below these studs. Nuts 23 are adapted to be screwed upon the studs so as to overlap the closure 19 and hold it securely in position. When, however, it is desired to remove the closure, the nuts are unscrewed from the studs and the closure is then swung so as to escape the lower edge of the wall 5. Said closure can then be pushed upward, so as to escape the brackets 20, this movement being permitted

in view of the provision of the slots 22, which receive the threaded lugs during this upward movement of the closure.

Secured upon the corner-standards of the casing and in contact with the inner faces of the end walls of said casing are hook-like brackets 24, which constitute seats for supporting-strips 25, extending longitudinally of the casing above the grate-bars and adjacent to the side screens. These bars 25 are provided at desired intervals with recesses 26, extending into the upper faces thereof. These recesses constitute seats for the lower pipes of vertical coils 27, preferably disposed in parallel planes, as shown particularly in Fig. 2. The lower pipes of these coils are all connected to the steam-supply pipe 28, which extends transversely within the casing adjacent one end, and the upper pipes of the coils are preferably connected at one end by a cross-pipe 29, by the provision of which steam-pressure within all of the coils is sure to be equalized. Each coil projects at its upper end from one end of the casing, as shown at 30, and has a screw-cap 31 thereon provided with a small vent 32, which permits the escape of the steam.

It is of course understood that any desired number of coils 27 may be used within the casing, and one or more of these coils has a series of vent-tubes 33 secured to it. These tubes are open at both ends and extend above the casing, while the lower ends are supported at suitable distances above the grate-bars. The tubes are preferably held in place by yokes 34, which embrace them, and have their threaded ends secured within plates 35, said plates and tube bearing upon opposite portions of the coil. This construction and arrangement of parts are clearly illustrated in Fig. 2. Each of the tubes 33 has a plurality of apertures 36 formed therein, said apertures constituting the outlets for the moisture driven from the material within the casing. It might be stated that any desired means may be employed for maintaining the coils in upright positions. For this purpose I preferably utilize cross-strips 37, which are secured to the corner-standards of the casing and have recesses 38 in their lower faces in which the upper pipes of the coils are seated. The side walls of the casing are preferably inclined outward, as shown at 39, so that the upper portion of the casing is in the form of a hopper into which material can be conveniently discharged.

When it is desired to heat sand or gravel, the same is dumped into the bottom of the casing and will be supported by the grate-bars and will surround the heating-coils and the vent-tubes. When steam is directed into the coils, it will of course circulate through them and thoroughly heat the material contacting therewith. The moisture contained within said material will be driven outward

through the screens 6 and 10, upward through the top of the casing, and inward through the openings 36 and into the tubes 33. Obviously with these numerous provisions for the escape of moisture the contents of the casing can be very quickly dried. Moreover, said casing can be constructed to hold a very large amount of sand or gravel, it merely being necessary to provide enough coils and vent-tubes to meet the requirements. As the sand or gravel dries it will fall through the apertures in the grate-bars, and this discharge may be accelerated by actuating the lever 17 so as to slightly rock the bars. By swinging the bars to the limit of their movement the contents of the casing will be quickly discharged therebetween. Should large stones or other material accumulate on the grate-bars and interfere with the discharge of the sand, &c., the closure 19 can be removed in the manner hereinbefore stated, and by inserting a rod or scraper above the bars the undesirable accumulations can be easily removed.

The preferred form of the invention has been set forth in the foregoing description; but I do not limit myself thereto, as I am aware that modifications may be made therein without departing from the spirit or sacrificing the advantages thereof. For instance, the end wall adjacent the headers 38 and 29 can be made removable, so as to permit access to be readily had thereto, so as to permit repairs to be easily made. I also reserve the right to make such other changes as may fairly fall within the scope of the claims.

What is claimed is—

1. In a drier of the character described the combination with a casing having screens therein constituting inner walls; of heating-pipes exposed within the casing, and apertured vent-tubes supported between said pipes.
2. In a drier the combination with a casing having inner walls constituting screens; of heating-coils disposed within the casing, and apertured vent-tubes secured to and supported above the bottom of the casing, said tubes having open ends.
3. In a drier the combination with a casing having inner walls constituting screens; of recessed strips detachably mounted within the casing, vertical heating-coils seated within said recesses, and apertured vent-tubes secured to and supported above the bottom of the casing by said coils.
4. In a drier the combination with a casing having inner walls formed of fabric; of brackets within the casing, recessed supporting-strips detachably mounted within the brackets, vertical heating-coils seated within the recesses, and recessed holding-strips secured within the casing and engaging the upper portions of said coils.
5. In a drier the combination with a cas-

ing having inner walls formed of fabric; of brackets within the casing, recessed supporting-strips detachably mounted within the brackets, vertical heating-coils seated within the recesses, recessed holding-strips secured within the casing and engaging the upper portions of said coils, and apertured vent-tubes secured to, and supported above the bottom of the casing by, the coils, said tubes being open at their ends.

6. In a drier the combination with a casing having inner walls of metal fabric, and heating-coils within the casing; of grate-bars pivotally mounted within the casing, means for simultaneously rocking the bars, and a detachable closure extending across the ends of said bars.

7. In a drier the combination with a casing having inner walls of metal fabric, and a heater within the casing; of apertured grate-bars, trunnions extending therefrom and supported by the sides of the casing, means for simultaneously rocking the bars, brackets, a closure detachably supported by said brackets and extending over one end of the bars, and means for securing the closure against displacement. 20 25

In testimony that I claim the foregoing as my own I have hereto affixed my signature in the presence of two witnesses.

GEO. L. WEBB.
